CLOTHING CONTAINER

Elliot A. Miller, New York, N. Y.

Application August 15, 1934, Serial No. 739,844

2 Claims. (CL. 312—144)

This invention pertains to storage containers for receiving and protecting clothing or other articles from moths, dust, dirt, or other destructive agencies and the same has particular reference to a container which includes a pair of closures so constructed and arranged as to overlie in superimposed relation, when the container is closed, to effectively seal the same.

The invention broadly comprehends a storage container of the cabinet type in which the cabinet structure is provided with a doorway in one of its vertical sides, together with a pair of closures hingedly connected with the cabinet structure at opposite sides of the doorway so as to effectively seal the doorway when the same is closed.

The invention more particularly provides a cabinet or container composed of a main body section forming the side walls and inner and outer closures therefor, and flanged end sections telescopically fitted over the opposite ends of the body section, the flanged end sections being provided with inwardly directed abutment strips against which the end portions of the inner closure abuts, the outer closure being of a length to extend beyond the end edges of the inner closure and to overlie the flanges of the end sections to provide a plurality of stepped contact surfaces disposed in different planes.

The inwardly directed abutment strips of the end sections further provide means which are adapted to be engaged by fastening elements which extend through the main body section and the flanges of the end sections for releasably securing the end sections to the main body section in a rigid closely fitting set-up relation.

The invention is particularly directed to a container composed of separable sections, each of which sections is constructed of cardboard, corrugated paperboard or other light weight stock which, when assembled, provides a convenient container for the storage of wearing apparel and which container is impervious to moths, dust, dirt or other destructive agencies.

With these and other objects in view, the invention is set forth in the following specification and accompanying drawing wherein there is disclosed a preferred form of the invention, while the claims cover other variations and modifications thereof.

In the drawing:

Fig. 1 is a perspective view on a relatively reduced scale, illustrating the container constructed in accordance with the invention and with the closures swung to open relation.

Fig. 2 is an enlarged vertical sectional view

taken approximately on a plane indicated by the line 2—2 in Fig. 1, with the closures swung to closed relation.

Fig. 3 is an enlarged horizontal sectional view taken approximately on line 3—3 of Fig. 2.

Fig. 4 is an enlarged fragmentary perspective view of the forward portion of one of the end sections.

Referring to the drawing by characters of reference, A designates generally a container which may be erected in endwise vertical relation to constitute a wardrobe or cabinet for garments to be suspended or hung therein, or which may be supported on the rear side wall thereof to provide a chest for the storage of clothing during the off seasons.

In the embodiment illustrated, the container is shown as a wardrobe or cabinet and which consists of a body or wall section 10 and similar end sections 11 and 12 which interfit with the body 10 or wall section 10 to complete the wardrobe or cabinet. The body or wall section 10 is preferably constructed from a blank of plain or corrugated cardboard, paper board, or other light weight stock, which is scored or bent on vertical lines to define a rear wall 13, opposite side walls 14 and 15, an inner closure 16, hingedly connected to the forward vertical edge of the side wall 15, and an outer closure 17, hingedly connected to the forward vertical edge of the side wall 14. The inner closure 16 is of lesser height than the main wall section 10 and is provided along its free vertical edge with a hingedly connected flap 18 which is adapted to impinge flatly against the inner face of the side wall 14 when the closure 16 is swung to closed relation. The outer closure 17 is of the same height as the height of the body or wall section 10 and is provided with a plurality of vertically spaced closure straps 19 secured against the outer face thereof and which are provided with fastening elements adapted to releasably engage cooperating elements carried by the outer face of the side wall 15 for securing the outer closure in closed position overlying, in superimposed relation, the inner closure 16.

The end sections 11 and 12 are substantially identical in construction and may be constructed from a blank of corrugated cardboard, paperboard or other light weight stock, which is fashioned to provide a rectangular panel 21 and inwardly directed marginal flanged edges 22 which telescopically fit over the rear and side walls of the body or wall section 10. The forward flanged edges of the end sections are each provided with an inwardly directed abutment strip 23 formed of

corrugated cardboard or other light weight material, which is secured against the inner face thereof by metal stitches 24 or equivalent securing means. The abutment strips 23 extend laterally across the forward side of the container between the opposite walls 14 and 15 and have rearwardly directed rectangular terminals or extensions 25 at each side thereof which engage against the inner surfaces of the side walls 14 and 15 respectively. The terminals or extensions 25, the side walls 14 and 15, and the flanged edges of the end sections 11 and 12 are provided with registering apertures for receiving a fastening element 26 for securing the body section and the end section in set-up relation.

The abutment strips 23 provide a stepped construction with the end sections 11 and 12 against which the end portions of the inner closure 16 abut when swung to closed relation with the closure flap 18 tightly impinged against the inner surface of the side wall 14 and with the end edges 27 impinged against the edges of the extensions 25 so as to tightly seal the closure and to prevent the entrance of moths, dust or other destructive agencies. The outer closure 17 being of the same height as the body or wall section 10, when swung to closed relation, overlies in superimposed relation, the inner closure 16 and extends beyond the end edges thereof so as to seal the joints between the inner closure 15 and the end sections 11 and 12. The extreme end portions of the outer closure 17 abut against the forward flanged edges of the end sections 11 and 12 to thereby effectively seal the inner closure and to provide a structure which is substantially impervious to the entrance of destructive agencies.

What is claimed is:

1. A storage container for clothing, including a body section and flanged end sections telescopically fitted over the opposite ends of the body section, said body section having a rear wall, a pair of opposed side walls defining an

open front and inner and outer closures hingedly connected to the forward edges of the side walls with the outer closure of a size to overlie the end edges of the inner closure and for engagement against the forward flanged edges of the end sections for closing and sealing the open front of the container, an abutment strip extending across and protruding inwardly beyond the inner edges of each of the flanged end sections at the open front to provide a sealing surface with which the inner closure engages, the said abutment strips each having angularly disposed terminals engaging against the inner surfaces of the side walls, and means securing the said terminals thereto and to the flanges of the end sections.

2. In a container for the storage of clothing, a body section including side walls and inner and outer closures hingedly connected to opposite side walls respectively, end sections each having inwardly directed flanged edges telescopically fitted over the ends of the side walls, an inwardly directed abutment strip secured against the inner face of the forward flanged edge of each of the end sections against which strips the inner closure abuts when in closed relation, and said abutment strips each having angularly disposed, rearwardly extending terminals, engaging the inner faces of the opposite side walls respectively, the said inner closure having a closure flap adapted to impinge against the inner face of the side wall to which the outer closure is hingedly connected, the outer closure being of a size to overlie, in superimposed relation, the inner closure, to extend beyond the end edges thereof and to abut against the forward flanged edges of the end sections when in closed relation, and means securing the said terminals to opposite side walls and to the flanges of the end sections for connecting the sections in closely fitting set-up relation.

ELLIOT A. MILLER.
